UNITED STATES PATENT OFFICE.

GEORGE COLVIN KENNEDY, OF WATERLOO, IOWA.

FEEDING DEVICE.

1,380,564.

Specification of Letters Patent. Patented June 7, 1921.

Application filed April 12, 1920. Serial No. 373,236.

To all whom it may concern:

Be it known that I, GEORGE COLVIN KENNEDY, a citizen of the United States of America, and a resident of Waterloo, Black Hawk County, Iowa, have invented certain new and useful Improvements in Feeding Devices, of which the following is a specification.

My invention relates to improvements in feeding devices, particularly for use by hogs, and the objects of my improvements are, first, to supply a tilttable feeding vessel, operable by the animal in shifting the vessel from a closed position relative to a source of supply into a feeding position receptive to a renewed supply, and second, to provide means whereby this feeding vessel, when left by the animal, will automatically return to a closed position, shutting off said supply, while evacuating its unconsumed contents.

These objects I have accomplished by the means which are hereinafter described and claimed, and which are illustrated in the accompanying drawings, in which Figures 1, 2 and 3 are similar vertical medial longitudinal sections of my improved feeding device, with parts broken away, and in which differently modified kinds of feeding vessels are shown; Fig. 4 is a front elevation of said device, with the upper part of the hopper broken away and the feeding vessel shown in cross section, and Fig. 5 is a perspective view of the feeding vessel shown in said Fig. 3.

Similar numerals of reference denote corresponding parts throughout the several views.

10 is a hopper whose diminished lower part has an opening incased by the widened upper part of a depending spout 8 secured by bolts 9, the spout preferably sloping forwardly. This hopper may be fixedly supported in any desired manner, as by fixed standards 11 and 13 secured thereto by bolts 45 12 and 14. These standards may be secured to a flooring 15 below the hopper and a raised platform 16 may be mounted on the forward portion of said flooring.

1 is an open top feeding vessel whose rear end may be thickened at 2 as shown in Fig. 1, or may be provided with a weight 7 secured to the bottom thereof as shown in Figs. 2 and 3, the body of the vessel being made of thin material. This feeding vessel 55 may be swingingly suspended beneath the spout 8 in any desired manner, the spout

extending into the vessel, but preferably the vessel is so hinged or pivoted intermediately of its ends, as to be in an unbalanced condition or so that the rear end thereof will 60 overweight the forward end to tilt the forward end upwardly, this being its normal position, and the shape of the vessel is such that in this position only, the uptilted bottom of the vessel completely closes contact- 65 ingly the open lower end of said spout. In order to prevent undue lengthening of the rear part of the vessel, the weight 7 is applied thereto.

For convenience and suitable supporting 70 of the vessel 1, the vessel may be hung pivotally and removably on fixed pintles 3 extending oppositely laterally and horizontally from the sides of the spout 8, the ends of the pintles extending into curved bearing 75 brackets 4 on the inside walls of the sides of the vessel. This permits of the lifting and removal of the vessel when it is desired to clean it.

A hog may press its lower jaw on the 80 rearwardly curved forward end of said vessel to rock the vessel to the feeding position shown by dotted lines. Feed will then flow through the spout 8 into the vessel replenishing it constantly as the contents are consumed, but when the animal leaves the vessel, the latter returns to a closed position, as shown in full lines, due to the superior gravity of its rear part. It will be seen that the shape and suspension of said vessel is 85 such that when in the feeding position, its bottom is inclined forwardly, facilitating replenishment of its contents, while in its closed position, its bottom is tilted rearwardly, causing any unconsumed contents 90 to flow past said spout into the rear part of the vessel, there to be retained until another actuation, when it returns forwardly for consumption. Feed is, therefore, not wasted by this device but is continuously 100 and completely consumed.

I have shown modified forms of the feeding vessel in Figs. 2 to 5 inclusive. In Fig. 2, the rear wall of the feeding vessel is omitted, but spaced pairs of ribs 5 are positioned on the rear ends of the inner side walls of the vessel to slidably and removably receive a closure or cross-plate 6, which suffices to close the rear end of the vessel when desired. Said closure 6 may be removed so that when the vessel tilts back to a closed position, any unconsumed contents 110

therein may flow rearwardly out of the vessel upon the flooring 15 or into an open removable receptacle 17 thereunder.

I have provided releasable securing means 5 for holding the vessel 1 in its lowered or open position as shown in Fig. 3. This may be a lug 22 secured on the under forward part of the vessel by a rivet 21 to be engaged by an end of a catch-bar 20 movable through orificed guides 19 on a base 18 secured to the platform 16.

It will be observed that in its closed position, the transverse wall of the forward end of said vessel contacts with the rearwardly sloping forward wall 10 of the hopper, preventing entrance of rain and keeping out birds or dust.

It should be noted that the hanging of the vessel 1 at a point intermediate its ends 20 below a diminished hopper, permits it to be tilted to close either end against the abutting part of the hopper when such end is tilted upwardly, and this exposes the other end open, whereby either end may be a feeding receptacle. Thus, referring to Figs. 1 and 2, feed which has slid down into the closed end 2 of Fig. 1, or against the removable end 6 of Fig. 2, may be consumed by small animals or even fowls, the other 25 higher end being used by larger animals. This allows feeding by one device from opposite sides of the hopper, an economy in construction.

The form and arrangement of my device 30 is very suitable for the grouping of any desired number thereof, side by side, so that they may be used to supply different kinds of feed as desired.

Having described my invention, what I 40 claim as new, and desire to secure by Letters Patent, is:

1. In a feeding device, a hopper, and an open top feeding vessel pivotally mounted intermediate its ends, one end of said vessel 45 being terminally closed to serve as a feed receptacle and the opposite end being terminally open to serve as a delivery chute, and into which the hopper extends in such a relation to the vessel that in one position of the vessel the upper surface of its bottom closes the delivery orifice of the hopper.

2. In a feeding device, an open vessel suspended pivotally intermediate its ends, and a hopper positioned above and delivering 50 into said vessel, said vessel when tilted in one direction closing the delivery opening of the hopper by the upper face of the bottom of the vessel, and the vessel in either of oppositely tilted positions closing one or the 55 opposite end of the vessel against the abutting part of the hopper.

3. In a feeding device, a hopper, an open top feeding vessel pivotally mounted between its ends in an unbalanced condition, 60 the hopper opening being closed by said

vessel when the latter is in its normal unbalanced state, and said vessel having its outer end wall shaped to close against the hopper when said hopper opening is closed by the vessel.

4. In a feeding device, a hopper having a delivery spout, and an open top feeding vessel pivotally mounted to inclose the delivery end of said spout to normally hang closing the delivery opening of the spout with a 75 part of its surface and with its open outer end closed against the abutting outer wall of the hopper.

5. In a feeding device, a hopper having a delivery spout and a wall inclined downwardly and rearwardly toward said spout, and an open top feeding vessel pivotally mounted in an unbalanced condition adapted to normally contact with and close the delivery end of its spout and at the same 85 time close its open end against the said inclined wall of the hopper.

6. In a device of the character described, a hopper having a delivery-opening, an elongated open top vessel under said opening 90 and whose opposite ends are terminally closed, said vessel being pivotally supported intermediate its ends in an unbalanced condition to close its outer end opening against the abutting parts of the hopper while exposing its inner end opening when tilted appropriately, the bottom of the vessel in said tilted position thereof closing the delivery opening of the hopper.

7. In a feeding device, a hopper, and an 100 open top feeding vessel suspended in an unbalanced condition adjacent to said hopper to receive therefrom, having one end closed and its opposite end terminally unobstructed, said vessel being suspended to normally close the delivery opening of the hopper, movable away to receive therefrom, and when closing said delivery opening to be inclined to evacuate its contents from said unobstructed end.

8. In a feeding device, a hopper, and an open top feeding vessel movably supported adjacent to said hopper to receive therefrom, having one end closed and its opposite end open, said vessel being suspended and 115 weighted to normally close the delivery opening of the hopper, and movable away to receive therefrom.

9. In a feeding device, a hopper, and a vessel removably supported in an unbalanced condition adjacent to said hopper to receive therefrom, having its outer end closed and its opposite end terminally open, said vessel being positioned to normally close the delivery opening of the hopper, movable away to receive therefrom, and when closing said delivery opening to be inclined to evacuate its contents from said open end, and removable means for closing the said open end of said vessel.

10. In a feeding device, a hopper, and an open top feeding vessel detachably suspended adjacent to said hopper to receive therefrom, having one end closed and its opposite end open, said vessel being suspended to normally close the delivery opening of the hopper, movable away to receive therefrom, and in both said positions having its bottom inclined away from the horizontal.
11. In a device of the character described, a hopper having a diminished delivery part, an open top vessel suspended pivotally below said delivery part to project oppositely at both ends therefrom, said vessel and delivery part of the hopper being so relatively positioned that when either end of the vessel is tilted upwardly, it is closed against the abutting part of the hopper, and when one end of the vessel is tilted upwardly, the upper face of its bottom closes the said delivery part.
12. In a device of the character described, a hopper with a terminal opening, a vessel pivoted intermediate its opposite ends under said hopper opening, the middle upper face of the bottom of said vessel closing said opening normally, and the opposite end parts of the vessel serving alternately as feed holders as the vessel is tilted to and from.

Signed at Waterloo, Iowa, this 8th day of April, 1920.

GEORGE COLVIN KENNEDY.
